UNITED STATES PATENT OFFICE

2,436,716

INSERTABLE AND DETACHABLE ARCH-SUPPORTING UNIT FOR FOOTWEAR

James A. Fikany, Carbondale, Pa.

Application April 21, 1945, Serial No. 589,647

5 Claims. (Cl. 36—71)

1 My present invention is a novel and improved cushioning and arch-supporting insertable and detachable unit or pad to be fitted into boots and shoes after they are otherwise completed, which insertable unit has, preferably, also an adjustable arch-supporting element enclosed in the cushioning portion of the unit.

The present invention is an improvement over that of my prior adjustable arch Patent No. 2,044,751, issued June 16, 1936, wherein I have illustrated, described, and claimed an adjustable arch supporting element built into the shoe structure itself between the insole and outsole of a standard type of shoe. In my said prior patent, however, the adjustable arch-supporting element was rigidly secured to the heel portion of the shoe structure, preferably to the heel itself, to facilitate the adjustable feature and the raising and lowering of the arch support, explained in my said patent, which lifted and lowered the insole of the shoe.

In my present invention I have devised an improved detachable and insertable pad or unit, having a cushioning and foot-supporting element and an adjustable arch-supporting feature which may be moved, adjusted, and secured in desired position for the foot of the individual wearer, for positioning a metatarsal arch-supporting element in proper position for the wearer.

In my said prior patent, a novel and important feature was the raising and lowering of the arch-supporting element under the insole; but in my present invention, which comprises an insertable and removable unit, the adjustment of the metatarsal supporting element is of prime importance, as the insertable unit or pad and cushioning member itself constitutes a lifting and supporting feature for the longitudinal arch of the wearer. By means of the removable and insertable unit construction of my present invention, varying types, thicknesses, and lengths of my insertable unit can be instantly fitted to any type of standard footwear and can be progressively changed from time to time for foot treatment, if desired, in addition to the range of adjustment provided by the shifting of the metatarsal arch within the insertable unit itself.

My present invention thus enables an adjustment and fitting to be made to the foot of the wearer by the adjustment of the metatarsal arch-supporting elements before the pad is inserted in the shoe, thus greatly facilitating accuracy, speed, and correct fitting in the adjustment desired for each individual user. Such an advantage was not possible in the prior construction.

2 wherein the adjustable element was underneath the insole of the shoe, requiring a cut-out part of the insole to be lifted, adjustments roughly made, and then the shoe fitted back on the foot, requiring a continuous cut-and-try method, and even then the fitting could not be as accurately obtained as where, in my present invention, the detachable pad is fitted to the foot of the wearer in full view of the operator and user.

10 Furthermore, my present improved insertable and detachable unit can be shifted from one pair of shoes to another which, of course, is a most important advantage.

15 In the manufacture of my present improved foot-cushioning and arch-supporting unit, I prefer to form the same of two layers of suitable yielding material which may be of leather, synthetic plastic, felt, or the like; and I fit between the two layers a cushioning element in addition to the cushioning features provided by the layers constituting the top and bottom portion of my unit. Secured also to the bottom layer is an adjustable element permitting ready adjustment of the metatarsal arch-supporting portion to fit 20 the particular individual wearer. This comprises a telescoping sliding element, having one end secured and the other adjustable longitudinally thereof, together with means for quickly locking the two sliding elements in adjusted position.

25 The top layer is secured over and around the cushioning and adjustable arch-supporting element and is provided with an opening or recess to enable the locking and unlocking to be readily reached, and the lengthwise adjustment to be

30 effected.

35 Further details, advantages, and novel combinations will be hereinafter more fully pointed out, described, and claimed.

Referring to the drawings illustrating a preferred embodiment of my present invention:

40 Fig. 1 is a plan view of the complete detachable cushioning and arch-supporting element;

45 Fig. 2 is a plan view with the upper foot-contacting layer removed;

Fig. 3 is a cross-sectional view on the line 3—3 of Fig. 1, and

Fig. 4 is a cross-sectional view on the line 4—4 of Fig. 1.

50 As shown in the drawings, my present unit comprises a lower layer 1 and an upper layer 2 of yielding sheet material, having a contour suitable to fit within the size, style, and type of shoe for which the insertable unit is to be utilized, these two layers being united around the marginal portion as by stitching 3. Any suitable or

desirable contour can be employed, preferably extending from the extreme rear heel of the shoe to the ball of the foot of the wearer in order to extend beyond the position of the metatarsal arch of the wearer. The upper layer 2 is provided with a line of cut, as indicated at 5, Fig. 1, defining a window, leaving a tongue or flap 6, which flap is in position to close and open said window and to fit over the locking element of the longitudinally adjustable part of the shoe to facilitate access thereto.

The longitudinally adjustable element comprises a fixed metal guiding element 10 rigidly secured by rivets, or the like, 11, 11 to the layer 1, and an adjustable sliding portion 15 fitted to slide over and upon the fixed guide 10, said guide being provided with edge flanges 12, 12 within which the shank of the sliding member 15 is retained. Preferably, these flanges may be extended and turned over at the top, as shown at 16, 16. Fig. 4, meeting in the middle and constituting a cover for the sliding member 15 and a support for this portion of the top layer 2. Fitted at each side of the telescoping members 10 and 15 are cushioning members 20, 20 extending lengthwise of the telescoping elements and of substantially equal or slightly greater thickness adjacent said telescoping members to provide a yielding support for the top layer 2 and, hence, for the foot of the wearer.

These cushioning members also constitute a longitudinal arch-supporting feature in addition to that afforded by the telescoping members. Said telescoping members may be constructed and arranged either to effect a raising and lowering during longitudinal adjustment or to be in the same arc or curve throughout the entire extent of their longitudinal adjustment, as a suitable unit can be fitted to the foot of the wearer to provide for the longitudinal arch-supporting extent desired, irrespective of the telescoping elements. This is a further advantageous feature of my present detachable unit.

The sliding portion 15 preferably terminates at its outer end in a metatarsal arch-supporting structure 21, having a convex surface for contact with the upper layer 2 merging into a slightly concave end portion 22; and, thereupon being bent backward in reverse direction to constitute a sliding support 23 for contact with the lower layer 1 and thus facilitate the longitudinal adjustment of the telescoping elements 10 and 15.

In order to secure the telescoping elements 10 and 15 in any lengthwise adjustment desired, I provide a slot 24 near the end portion of the element 15 which is engaged by a headed screw 25, having the shank extending thru said slot and into a threaded opening in the fixed element 10. Thus, a loosening of the screw 25 permits a relatively sliding cushion between the telescoping members 10 and 15 to provide lengthwise adjustment of the metatarsal arch support 21; whereupon, tightening of the screw holds the same in adjusted position, the flap 6 being readily raised for access to screw 25.

The operation and advantages of my improved invention will be readily appreciated. An appropriate unit to fit the size and style of the shoe of the wearer to which such unit is to be adjusted, which unit may be made and marked corresponding to the size of footwear, is readily selected, whereupon the unit itself is adjusted to the foot of the wearer with the advantages of full vision for the fitting and adjusting operation. Thereupon, the unit is applied to the shoe and

the assembly is complete. At any time the unit can be removed for further adjustment, thus effecting progressive treatments of the arch support and particularly the metatarsal arch-supporting feature; and, if necessary, additional units can be substituted or any of these units can be removed from one shoe and replaced in another pair of the wearer's shoes.

I claim:

1. A detachable arch-supporting and cushioning unit comprising an upper and a lower yielding layer united around their marginal contour, a longitudinally adjustable pair of telescoping elements, one of said pair being fixed to a selected one of the layers, and the other being longitudinally slidable relatively with said fixed member, the slidable member carrying a metatarsal arch support at its outer end, and a resilient cushioning element in the space alongside said telescoping elements and filling said space.

2. A detachable arch-supporting and cushioning unit comprising an upper and a lower yielding layer united around their marginal contour, a longitudinally adjustable pair of telescoping elements, one of said pair being fixed to a selected one of the layers, and the other being longitudinally slidable relatively with said fixed member, a resilient cushioning element in the spaces alongside both sides of said telescoping elements and filling said spaces, the slidable member carrying a metatarsal arch support convex at its outer end, said metatarsal arch support having its end turned in underneath its convex portion for facilitating sliding adjustment thereof.

3. A detachable cushioning and adjustable arch-supporting unit adapted to be assembled in a completed shoe, comprising a pair of layers of yieldable material united together, a pair of telescoping members secured between said layers and approximately in the lengthwise middle portion of said layers, having means for relatively longitudinal sliding action within said layers, a plurality of yielding cushioning elements lengthwise of and adjacent to said telescoping elements and of substantially equal thickness to said telescoping members, means to adjust said telescoping members in lengthwise adjusted position, and means to lock said members in said adjusted position, said locking means being accessible thru one of said layers.

4. An arch supporting unit for use in a completed shoe, comprising a base layer, a pair of curved telescoping members for providing a support for the longitudinal arch of the foot, one of said members being fastened to said base layer, the other of said members being provided with a convex portion for fitting under and supporting the metatarsal arch of the foot, means for variably positioning and securing said telescoping members with respect to each other for varying the size of the arch provided by said members, an upper layer secured to the base layer and enclosing the telescoping members, thereby providing an arch supporting unit readily positionable in and removable from the shoe, said upper layer being provided with a window for giving access to the said means for variably positioning and securing said telescoping members.

5. An arch-supporting unit for use in a completed shoe, comprising a pair of curved telescoping members for providing a support for the longitudinal arch of the foot, one of said telescoping members being provided with a portion for fitting under and supporting the metatarsal

arch of the foot, means for variably positioning and securing said telescoping members with respect to each other for varying the effective size of the arch provided by such members, upper and lower enveloping layers of sheet material secured to each other and enclosing the telescoping members, means in one of said layers of sheet material for giving access to said telescoping members for adjusting them, and means for securing one of said telescoping members to one of said layers of sheet material, for providing an arch supporting unit readily positionable in and removable from the shoe.
